UNITED STATES PATENT OFFICE

GEORGE U. MEYER, OF PROVIDENCE, RHODE ISLAND, ASSIGNOR TO PROVIDENCE STOCK COMPANY, A CORPORATION OF RHODE ISLAND

SELF-CLOSING EXTENSION DEVICE

Application filed April 8, 1931. Serial No. 523,678.

My present invention relates to extension devices for bracelets, watch straps, and the like, and particularly pertains to extension devices formed of a plurality of nested leaves.

It has been found that the locking of the extension device on the wrist after the extended bracelet or watch strap has been passed over the hand entails certain difficulties, as only one hand is available for bringing the extension plates into locking position. In addition, the thin, narrow extension plates used for ladies' bracelets are easily buckled the wrong way, thus resulting in frequent breakage of the delicate hinge sections.

The principal object of my invention is therefore to provide a resilient arrangement for urging the extension plates towards nested position, thus facilitating the locking of the plates and at the same time preventing swinging of the plates in the wrong direction.

The resilient urging of the plates towards nesting position necessitates a design of adjusting means for fitting the bracelet to the wrist that will interpose a minimum interference to the nesting operation. Another object of my invention is therefore to provide a length adjustment that does not project into the nesting space.

With these and other objects and advantageous features in view, the invention consists of a novel arrangement of parts more fully disclosed in the detailed description following and in the accompanying drawings, and more particularly defined in the appended claims.

In the drawings:

Fig. 1 is a top view of the novel extension in locked position;

Fig. 2 is a top plan view thereof, in extended position;

Fig. 3 is a bottom plan view, in extended position;

Fig. 4 is a perspective view showing the action of the folding springs;

Fig. 5 is a perspective view of a thin model extension device, showing a modified arrangement of the folding springs;

Fig. 6 is a longitudinal sectional view

through the cover member, showing the slotted adjustment plate; and

Fig. 7 is a perspective view of the adjusting plate.

It has been found desirable to provide resilient means for urging the plates of an extension device towards nested position. I have therefore utilized a plurality of springs, which are mounted on the hinge sections of the plates so as to resist swinging of the plates in the wrong direction and to urge the plates towards each other, thus simplifying the locking of the extension device and at the same time preventing breakage of the hinge portions of thin plates by inadvertent outward swinging; and I have devised a length adjustment that forms part of the extension device and does not project into the nesting space; and the following is a detailed description of specific extension constructions which embody the principles of my invention.

Referring to the drawings, the extension device 10 is used to extendibly connect the ends of a bracelet or watch strap band 11. The extension device includes a cover member 12, having side walls 13, means such as a length adjusting device 14 being provided at one end of the cover member to receive one end of the bracelet or watch strap. The other end of the cover member is adapted to hingedly receive an intermediate extension plate 15, which has spaced hinge sections 16, 17 mounted on a hinge pin 18 having its ends mounted in suitable openings in the side walls of the cover member. A coil spring 19 is mounted on the pin 18 between the spaced hinge sections 16, 17, with its extended ends 20, 21 respectively engaging the cover member and the extension plate 15 to resiliently urge the two towards contacting position.

A second intermediate plate 22, has spaced hinge portions 23 at one end in which a pivot pin 24 is mounted, a central hinge portion 25 on the intermediate plate 15 being positioned between the spaced hinge portions 23 and 26 hingedly mounted on the center portion of the pin 24.

A third intermediate plate 26 has spaced hinge portions 27 in which a pivot pin 28 is mounted, the plate 22 also having spaced

hinge portions 29 contiguous thereto and mounted on the pin 28 between the hinge portions 27. A coil spring 30 is mounted on the pin 28 between the hinge portions 29, and 5 has its extended ends 31 engaging the two plates 22 and 26 to resiliently urge them together, as shown in Figure 4.

An end plate 32 completes the specific extension device described, and has spaced hinge 10 portions 33 in which a pivot pin 34 is mounted, a central hinge portion 35 on the plate 26 being positioned between the hinge portions 33 in pivotal engagement with the pin 34. The end plate 32 preferably has side walls 36 and 15 means such as an end tubular portion 37 for receiving one end of bracelet or watch strap 11, the side walls having indentations 38 for releasable locking engagement with cooperating indentations 39 in the side walls of the 20 cover member, and the cover member having a finger tab or the like 40 to assist in releasing the locking engagement.

The springs 19 and 30 urge the intermediate plates together, these plates all being of less 25 width than the end plate to nest therein, the side walls of the end plate nesting within the side walls of the cover member. This construction thus facilitates locking, and prevents backward swinging of the several 30 plates.

Referring now to Figures 6 and 7, the preferred length adjustment includes a slotted adjustment plate 41 which has length adjustment slots 42 therethrough, the plate having 35 spaced retaining fingers 43 which are received in suitable openings 44 in the side walls 13, the plate 41 being spaced from the cover member to permit the passage of a depending lock finger 45 of an adjusting plate 46 therebetween. The adjusting plate 46 has means 40 such as a tubular portion 47 to receive the other end of the bracelet or watch strap 11, and is releasably held in position by indentations 48 on the side walls of the cover member 45 which snap past the side edges of the adjusting plate.

The specific extension device above described is suitable for the larger size bracelets and watch straps, but is difficult to apply to 50 thin, narrow bracelets and watch straps on account of the necessarily small width of the hinge sections, such as shown for example, at 27 and 29 in Figure 3. It is therefore preferred to mount the coil springs, designated 55 49, 50 in Figure 5, on the hinge pins mounted in the cover member 51 and the end plate 52 of a narrow extension device, these springs urging the first and third intermediate plates 53, 54 towards the cover member and the end 60 plate. Since this direction of the spring force pulls the free ends of the plates 53, 54 in the proper direction, the central intermediate plate 55 is also forced towards nesting position.

65 While I have described specific structural

embodiments of my invention, it is obvious that such changes in the relative arrangement, in the size of the parts, in the disposition and the mounting of the springs, as is found most suitable for different types of 70 bracelets and watch straps may be made, without departure from the spirit and the scope of the invention as defined in the appended claims.

I claim:

1. In an extension device, a cover member, band securing means at one end thereof, a plurality of hinged extension plates pivotally secured to the other end of the cover member and adapted to nest against said cover member, means comprising a plurality of spring means mounted on alternate hinges for urging said extension plates into nested position, and means releasably locking said extension plates in nested position, the outermost extension plate having band securing means at the free end thereof. 75

2. In an extension device, a cover member, band securing means at one end thereof, a plurality of hinged extension plates pivotally secured to the other end of the cover member, and adapted to nest into said cover member, means comprising a plurality of spring means mounted on alternate hinges for urging said extension plates into nested position, 80 and means releasably locking the last extension plate to the cover member to retain the nested plates in nested position, the outermost extension plate having band securing means at the free end thereof. 85

3. In an extension device, a cover device having a transversely slotted portion, an adjusting plate having a finger adjacent one end thereof selectively engageable with said slots to adjust the length of said extension device, means for releasably locking said adjusting plate in adjusted position and adjacent said cover device, a plurality of extension plates hingedly connected to said cover device, and bracelet securing means on the free end of said extension plates and on the other end of said adjusting plate. 95

4. In an extension device, a cover member, an adjustment plate secured to said cover member and having a plurality of transverse slots, an adjusting plate having a finger adjacent one end thereof selectively engageable with said slots to adjust the length of said extension device, means for releasably locking said adjusting plate in adjusted position and adjacent said cover device, a plurality of extension plates hingedly connected to said cover device, and bracelet securing means on the free end of said extension plates and on the other end of said adjusting plate. 105

In testimony whereof I affix my signature.
GEORGE U. MEYER.
